US00D905849S

(12) **United States Design Patent** (10) **Patent No.:** **US D905,849 S**
(45) **Date of Patent:** **** Dec. 22, 2020**

(54) **ON-BODY INJECTOR**

(71) Applicant: **AMGEN INC.**, Thousand Oaks, CA (US)

(72) Inventors: **Margaux Frances Boyaval**, Newbury Park, CA (US); **Sigrid Moeslinger**, New York, NY (US); **Lisa Nugent**, Malibu, CA (US); **Brian Stonecipher**, Newbury Park, CA (US); **Masamichi Udagawa**, New York, NY (US)

(73) Assignee: **AMGEN INC.**, Thousand Oaks, CA (US)

(**) Term: **15 Years**

(21) Appl. No.: **29/670,165**

(22) Filed: **Nov. 14, 2018**

(57) **CLAIM**

The ornamental design for an on-body injector, as shown and described.

DESCRIPTION

FIG. 1 is a perspective view of a new design for an on-body injector having a light source shown in a powered off state; FIG. 2 is a front view of the on-body injector of FIG. 1; FIG. 3 is a rear view of the on-body injector of FIG. 1; FIG. 4 is a right-side view of the on-body injector of FIG. 1; FIG. 5 is a left-side view of the on-body injector of FIG. 1; FIG. 6 is a top view of the on-body injector of FIG. 1; FIG. 7 is a bottom view of the on-body injector of FIG. 1; and, FIG. 8 is a perspective view of the on-body injector of FIGS. 1-7 showing the light source in a powered on state. The dashed lines are included for the purpose of illustrating environment and form no part of the claimed design. The stippling shown is included for the purpose of illustrating portions of the claimed design having a visual appearance (e.g., color, texture, glow, etc.) different from the immediately adjacent portions of the claimed design. The radiating lines are included for the purpose of illustrating a feature of the claimed design in an illuminated state, and form no part of the claimed design.

1 Claim, 5 Drawing Sheets
